MERCURY SWITCH

Uno C. Hedin and Carl H. Larson, Elkhart, Ind.,
assignors to The Adlake Company, a corpora-
tion of Illinois

Application June 10, 1935, Serial No. 25,818

12 Claims. (Cl. 200—112)

The purpose of this invention is to increase the current carrying capacity of mercury switches; to permit higher voltages to be used; to protect against switch failure by increasing the factor 5 of safety; and to achieve all of these advantages without materially increasing the cost of manufacture and without complicating to any appreciable extent the processes of fabrication.

Further and other objects and advantages will 10 become apparent as the disclosure proceeds and the description is read in conjunction with the accompanying drawing, in which

Fig. 1 is a sectional view showing a magnetically controlled mercury-displacement switch made in 15 accordance with this invention;

Fig. 2 is a cross sectional view through the displacer, the view being taken on the line 2—2 of Fig. 1;

Fig. 3 is a fragmentary, perspective view showing a form of the invention that is preferred for some installations;

Figs. 4—8 inclusive are fragmentary views showing further modifications of the invention.

It will be understood that the several embodiments of the invention shown in the drawing and hereinafter described have been selected for the purpose of disclosure, and the appended claims are not to be construed as limited to these specific forms, or any of them, unless required by the 20 prior art. Also, it will be understood that various changes can be made in the forms disclosed without departing from the spirit of the invention.

The invention is particularly applicable to switches of the type disclosed in Larson Patent 25 No. 1,967,247 in which a magnetically controlled plunger or displacer is vertically reciprocable within a hermetically sealed switch envelope having a mercury fill that is adapted to open or close the circuit through spaced electrodes in the envelope according to the position of the displacer 30 within the envelope.

It is customary in this type of switch to have one electrode continuously in contact with the mercury and another projecting upwardly through 35 the mercury but insulated therefrom (when the switch is in off position) by a glass sleeve fused on the electrode.

There is always a possibility in a switch of this type that the insulating sleeve surrounding the one electrode may crack, or break, in which case the circuit through the switch would be permanently closed. It is one of the purposes of this invention to insure against this possibility.

Referring now to the drawing, and particularly 40 to Fig. 1, a switch envelope is indicated at 16,

which may be of glass, or other suitable material, having a pair of electrodes 11 and 12, preferably of tungsten or molybdenum, which are pinch-sealed through the base of the envelope as indicated at 13. Each electrode has fused to it a glass 5 insulating sleeve 14 which extends from the pinch seal 13 of the envelope to a point 15 adjacent to the tops of the electrodes. In the embodiment of the invention shown in Figs. 1 and 2, the bared ends 16 and 17 of the electrodes 11 and 12, respectively, are bent over the insulating sleeve 14 10 in opposite directions and in order to save space, the bared ends may be twisted to an acute angle with respect to the vertical plane through the two electrodes.

A mercury fill 18 occupies the lower part of the switch envelope and normally has its level below the bent-over ends 16 and 17 of the two electrodes. The mercury level, however, may be shifted by energizing a coil 19 associated with the switch 20 which causes a displacer, generally designated 20, composed in part of magnetic material, to move 25 downwardly within the envelope and displace a sufficient quantity of mercury to bridge the overhanging tips of the electrodes 11 and 12, thus closing the circuit through the two electrodes. When the coil is de-energized, the displacer rises by buoyancy to the position shown in Fig. 1 and the circuit through the electrodes is broken.

The displacer may be of any suitable form but 30 is here shown as consisting of a sleeve 21, surrounding a glass sleeve 22, the two parts being held in fixed relative position by coil springs 23, preferably of tungsten or molybdenum, which frictionally engage the projecting ends of the glass 35 tube 22 and clamp hardened guide washers 24 of tool steel in place. The springs serve the double function of holding the component parts of the switch together and protecting the switch envelope from damage during shipment.

The coil 19 has an iron circuit associated with it which is substantially the same as that shown in Larson Patent No. 1,967,247 and no further description is deemed necessary here.

One of the particular advantages of this switch 45 over that disclosed in Larson Patent No. 1,967,247 is that double protection is afforded against the possibility of switch failure due to the cracking of the insulating sleeve surrounding the electrodes. For example, should the insulating sleeve 50 14 around one of the electrodes crack, the switch would not be short circuited because the other insulating sleeve would separate the electrodes 11 and 12.

Another inherent advantage is that higher 55

voltages can be used due to the increased dielectric strength separating the electrodes.

Furthermore, higher currents can be carried with a switch made in accordance with this invention due to the fact that only a small quantity of mercury is used to bridge the gap between the two electrodes with the result that the heating effect of the current through the mercury is confined to an area that is small in comparison 10 with the entire mercury fill.

The modified form of the invention shown in Fig. 3 is used where the switch is to carry exceptionally high voltages. The only difference between the form of the invention shown in 15 Figs. 1 and 2 and that shown in Fig. 3 is that in the former, the bent-over ends 16 and 17 of the electrodes 11 and 12 lie in planes making an acute angle with respect to the vertical plane through the sleeves 14, while in the later, the bent-over 20 ends lie in parallel planes that are at right angles to the plane through the sleeves 14. This latter arrangement has the advantage that there is a greater air gap between the exposed portions 25 of the electrodes, and the switch has a correspondingly greater voltage capacity. It has, however, the disadvantage that the overall dimension of the switch must be somewhat larger in order to permit the displacer to telescope over the electrodes.

30 Instead of having the bare ends of the two electrodes bent over in the same direction, they may be bent over in opposite directions, as shown in Fig. 4, and if desired, the insulating sleeves may be fused together, as indicated at 25.

35 Still greater current carrying capacity may be obtained by giving the downwardly extending ends of the electrodes 16 and 17 an upward bend, as indicated at 26 (see Fig. 5).

If a mercury to mercury contact is desired, 40 the upper ends of the insulating sleeves 14 may be spread apart and provided with cups 27 (Fig. 6), the edges of which are protected by annular ceramic lips 28 which are interlocked with the glass insulating sleeves.

45 The adjacent sides of the cups 27 may be fused together, as indicated at 29 (Fig. 7) in order to give the switch structure greater mechanical strength. A ceramic lip 30 may be provided as before.

50 In Fig. 8, a modification is shown in which the insulating sleeve 14 surrounding one of the electrodes (for example electrode 11) is provided with a mercury cup 31, the edges of which are protected by a ceramic lip 32, and the other electrode 55 has its insulating sleeve 14 extending only slightly above the low mercury level. Thus, when the displacer 21 is lowered, causing the mercury level to rise, the bared end 33 of the electrode 12 (Fig. 8) is first placed in contact with the mercury fill and then the circuit is finally made over the edge of the lip 32 by a mercury to mercury contact. Upon allowing the displacer to rise, the circuit is broken as soon as the mercury level falls below the top of the cup 31 with its 60 ceramic lip and the subsequent falling away of the mercury below the top of the insulating sleeve around the electrode 12 has no effect except to place the mercury at zero potential.

65 What we claim:—

70 1. A mercury switch of the class described comprising a vertical switch envelope, a mercury fill, a pair of electrodes of opposite polarity projecting through the fill, means for shifting the mercury level to bridge the electrodes with mercury 75 and hence close the circuit through the elec-

trodes, and an insulating sleeve on each electrode extending above the low level of the fill and exposing a portion of the electrode for contact with the mercury when the mercury is at its high level.

2. A mercury switch comprising a switch envelope, a mercury fill, a pair of electrodes of opposite polarity projecting upwardly through the fill, a displacer for shifting the mercury level to bridge the electrodes with mercury and hence close the circuit through the electrodes, and an insulating sleeve on each electrode insulating the electrodes from the mercury fill when the switch is in open circuit position and exposing a portion of the electrode for contact with the mercury 15 when the mercury is at its high level.

3. A mercury switch of the class described comprising a switch envelope, a mercury fill, a pair of electrodes of opposite polarity sealed through the base of the envelope and projecting upwardly through the fill, means for shifting the mercury level to bridge the electrodes with mercury and hence close the circuit through the electrodes, and means for insulating both electrodes 20 from the fill when the mercury level is at its lowest position within the envelope and exposing a portion of each electrode for contact with the mercury when the mercury is at its high level.

4. A mercury switch of the class described comprising a stationary switch envelope, a mercury fill, a pair of spaced electrodes of opposite polarity in the envelope projecting through at least a portion of the mercury fill, and adapted to be bridged by the mercury fill under predetermined conditions to close the circuit through the electrodes, and means for insulating both electrodes from the fill when the switch is in open circuit position and exposing portions of both electrodes 25 for contact with the mercury when the switch is in its closed circuit position.

5. In a mercury switch, a vertical switch envelope, a mercury fill, a displacer for shifting the mercury level and spaced electrodes of opposite polarity projecting upwardly through the mercury, said electrodes having insulating sleeves 45 extending above the low mercury level but short of the ends of the electrodes.

6. In a mercury switch, a vertical envelope of non-conducting material, a mercury fill, a pair of electrodes projecting upwardly through the 50 fill and insulated from the mercury to a point above the normal level of the mercury, and means for bridging the exposed ends of the electrodes with mercury, said means including a magnetically responsive displacer.

7. A mercury switch of the class described comprising a vertical switch envelope, a mercury fill, a pair of electrodes of opposite polarity projecting upwardly through the fill, means for shifting the mercury level to bridge the electrodes with mercury and hence close the circuit through the electrodes, and an insulating sleeve on each electrode extending above the low level of the fill and exposing a portion of the electrode for contact with the mercury when the mercury is at its high level, at least one of said electrodes comprising a conducting element having an end portion projecting from its sleeve and turned down to project 65 below the upper end of said sleeve.

8. A mercury switch of the class described comprising a vertical switch envelope, a mercury fill, a pair of electrodes of opposite polarity projecting upwardly through the fill, means for shifting the mercury level to bridge the electrodes with mercury and hence close the circuit through the 75

electrodes, and an insulating sleeve on each electrode extending above the low level of the fill and exposing a portion of the electrode for contact with the mercury when the mercury is at its high level, each of said electrodes comprising a conducting element having an end portion projecting from its sleeve and turned over and down in parallel planes oblique to the vertical plane through the pair of sleeves.

10 9. A mercury switch of the class described comprising a vertical switch envelope, a mercury fill, a pair of electrodes of opposite polarity projecting upwardly through the fill, means for shifting the mercury level to bridge the electrodes with mercury and hence close the circuit through the electrodes, and an insulating sleeve on each electrode extending above the low level of the fill and exposing a portion of the electrode for contact with the mercury when the mercury is at its high level, each of said electrodes comprising a conducting element having an end portion projecting from its sleeve and turned over and down on opposite sides of said sleeves in parallel planes substantially normal to the vertical plane through the pair of sleeves.

15 10. A mercury switch of the class described comprising a vertical switch envelope, a mercury fill, a pair of electrodes of opposite polarity projecting upwardly through the fill, means for shifting the mercury level to bridge the electrodes with mercury and hence close the circuit through the electrodes, and an insulating sleeve on each electrode extending above the low level of the fill and exposing a portion of the electrode for contact with the mercury when the mercury is at its high level, said insulating sleeves being joined

together and constituting effectively integral parts of a unitary element.

11. A mercury switch of the class described comprising a vertical switch envelope, a mercury fill, a pair of electrodes of opposite polarity projecting upwardly through the fill, means for shifting the mercury level to bridge the electrodes, and an insulating sleeve on each electrode extending above the low level of the fill and exposing a portion of the electrode for contact with the mercury when the mercury is at its high level, the sleeve of at least one of said electrodes terminating at its upper end in a cup surrounding the end of the electrode and adapted to contain a quantity of mercury.

15 12. A mercury switch of the class described comprising a vertical switch envelope, a mercury fill, a pair of electrodes of opposite polarity projecting upwardly through the fill, means for shifting the mercury level to bridge the electrodes with mercury and hence close the circuit through the electrodes, and an insulating sleeve on each electrode extending above the low level of the fill and exposing a portion of the electrode for contact with the mercury when the mercury is at its high level, the sleeve of one of said electrodes terminating at its upper end in a cup surrounding the end of the electrode and adapted to contain a quantity of mercury, and the sleeve of the other of said electrodes terminating below the level of said quantity of mercury and exposing its electrode for direct contact with the mercury fill when said fill is at its high level.
